UNITED STATES PATENT OFFICE.

STEPHEN H. PURDY AND RAYMOND B. CARSON, OF FULTONVILLE,
NEW YORK.

WOVEN-WIRE FENCE.

SPECIFICATION forming part of Letters Patent No. 591,294, dated October 5, 1897.

Application filed February 10, 1897. Serial No. 622,848. (No model.)

To all whom it may concern:

Be it known that we, STEPHEN H. PURDY and RAYMOND B. CARSON, citizens of the United States, residing at Fultonville, in the county of 5 Montgomery and State of New York, have invented certain new and useful Improvements in Woven-Wire Fences; and we do declare the following to be a full, clear, and exact description of the invention, such as will enable others skilled in the art to which it appertains to 10 make and use the same.

Our invention has relation to improvements in woven-wire fences; and the object is to provide a simple, cheap, and durable fence which 15 will readily adjust itself to the lay of the land.

To this end the novelty consists in the construction, combination, and arrangement of the same, as will be hereinafter more fully described, and particularly pointed out in the 20 claim.

In the accompanying drawings the same reference-characters indicate the same parts of the invention.

Figure 1 is a perspective view of a section 25 of our improved fence comprised between two fence-posts, and Fig. 2 is an enlarged detail plan of a section of the same.

The horizontal wires comprise two strands 1 and 2, forming a cable with contiguous eyes 3 4 arranged at suitable intervals, the direction of the twist of the strands being reversed 30 at each set of eyes, as shown.

The strands 5 6 of the vertical spacing-cable are then passed downwardly from the top 35 line of horizontal wires through the eyes 3 4 in each line of horizontal wires, and their lower ends are twisted at 7, immediately below the bottom line of horizontal wires, to permanently secure them at this point. The vertical parallel strands 5 6 are then grasped 40

about midway between the horizontal wires by a pair of clamping-jaws, (not shown,) and a horizontal rotary motion imparted to said jaws forms a right-hand and a left-hand cable-twist to the spacing-wires between each 45 contiguous pair of horizontal fence-wires.

It will of course be understood that any number of the vertical spacing-wires may be employed, corresponding to the use to which the fence is applied, and it will be observed 50 that the point of junction of the longitudinal wires with the vertical spacing-wires forms a double hinge-joint, which is a very desirable feature in this style of fence. This construction forms an interlocking hinge-joint at each 55 connecting-point and permits the fence to readily adapt itself to the varying undulations of the ground without impairing its strength or efficiency.

Having thus fully described our invention, 60 what we claim as new and useful, and desire to secure by Letters Patent of the United States, is—

A woven-wire fence, comprising a twisted horizontal cable provided at intervals with 65 contiguous eyes 3 4, the direction of the twist being reversed between each two pairs of eyes, in combination with a series of twisted vertical cables interlocking with said eyes, and having the direction of their twist reversed 70 between each two contiguous horizontal cables, substantially as shown and described.

In testimony whereof we hereunto affix our signatures in presence of two witnesses.

STEPHEN H. PURDY.
RAYMOND B. CARSON.

Witnesses:

M. F. WEMPLE,
CHARLES DOPP.
